UNITED STATES PATENT OFFICE.

HARRY A. DEVER, OF WILMETTE, ILLINOIS.

DESIGN FOR A REAR SIGNALING DEVICE FOR AUTOMOBILES.

58,999.

Specification for Design. Patented Sept. 13, 1921.

Application filed January 6, 1921. Serial No. 435,525. Term of patent 14 years.

To all whom it may concern:

Be it known that I, HARRY A. DEVER, a citizen of the United States, residing at Wilmette, in the county of Cook and State of Illinois, have invented a new, original, and ornamental Design for a Rear Signaling Device for Automobiles, of which the following is a specification, reference being had to the accompanying drawing, forming a part thereof.

Figure 1 is a front elevation, showing my new design; and

Fig. 2 is a side or edge elevation of the same.

I claim:

The ornamental design for a rear signaling device for automobiles, as shown.

In testimony whereof I have hereunto signed my name in the presence of two subscribing witnesses.

HARRY A. DEVER.
